REVOLVABLE BATHROOM CHEST AND HAMPER COMBINATION

Edward Kelly, Chicago, Ill., assignor to Wolff Appliance Corporation, Long Island City, N.Y., a corporation of New York

Filed July 2, 1962, Ser. No. 70,758

Term of patent 14 years

(Cl. D4—3)

FIG. 2

FIG. 1 is a perspective view of a revolvable bathroom chest and hamper combination, embodying my new design, and showing the front and one side thereof, with the hamper in open position.

FIG. 2 is a similar view showing the opposite side and rear of the chest.

The top and bottom portions of the article are conventionally plain, with the exception of the pole elements, which extend substantially from the center top and center bottom of the combination, the elements being substantially cylindrical in cross section throughout.

I claim:

The ornamental design for a revolvable bathroom chest and hamper combination, as shown and described.
